UNITED STATES PATENT OFFICE

JOE N. SUMMERS, OF MISSION, TEXAS

DIPPER OR BUCKET FOR EXCAVATING MACHINES

Application filed June 14, 1930. Serial No. 461,172.

This invention relates to excavating machines, and more particularly to an improved dipper or bucket for excavating machines of that type embodying a boom, a dipper handle 5 carried by the boom and at least two hoisting drums.

The invention has for one of its objects to provide a dipper or bucket which shall be of such construction and adapted to be so 10 connected to the dipper handle as to permit it to be operated as a reversed dipper or as a pull shovel or as a drag scraper bucket, to the end that the machine may be used for excavating canals, trenches and burrow pits, for 15 building levees, and for other excavating work in general.

The invention has for a further object to provide a dipper or bucket of the character stated which shall be adapted to be connected 20 to the dipper handle and operated in such manner as to obviate the necessity of the use of a drop bottom therefor, to the end that the objections incident to the use of such bottoms and their latches and springs shall be 25 avoided.

With the foregoing and other objects in view, the nature of which will appear as the description proceeds, the invention consists 30 in the construction, combination and arrangement of parts hereinafter fully described and claimed, and illustrated in the accompanying drawings, wherein:—

Figure 1 is a view in side elevation of an excavating machine equipped with a dipper 35 or bucket constructed in accordance with my invention, the dipper or bucket being shown by solid lines in load receiving position and by dotted lines in load sustaining position;

Figure 2 is a view in side elevation of the 40 machine with the dipper or bucket shown by solid lines in load sustaining position and by dotted lines in load discharging position;

Figure 3 is a view in rear elevation of the 45 machine, and

Figure 4 is a sectional view taken on a vertical plane extending longitudinally and centrally through the dipper or bucket and the lower end of the dipper handle of the machine.

50 Referring in detail to the drawings, 1 des-

ignates the front part of an excavating machine of the type referred to. 2 designates the boom and 3 the dipper handle of the machine. The boom 2 is pivotally mounted in the usual manner, as at 4, and is provided at 55 its upper or free end with a shaft 5 upon which are mounted sheaves 6 and 7. The boom 2 is adapted to be raised and lowered through the medium of the usual cables 8 which pass about the sheaves 6 and are connected to a winding drum, not shown. The dipper handle 3 is connected in the usual manner to the boom 2 for rocking and sliding movement with respect thereto, and has secured to the lower end thereof my improved dipper or bucket 9. The means for connecting the dipper handle 3 to the boom 2 are not shown since the construction of such means is well understood.

The dipper or bucket 9 embodies top, bottom, rear and side walls that are fixedly connected together, and it is fully open at its front or filling side. The dipper 9 is provided with a bottom cutting lip 10 and side cutting lips 11, and carried by the lips and 70 teeth 12. The bucket 9 is pivotally connected at its upper front corner, as at 13, to the lower end of bracket plates 14 that are secured, as at 15, to the lower end of the dipper handle 3. The dipper or bucket 9 embodies top, bottom, rear and side walls that are fixedly connected together, and it is fully open at its front or filling side. The dipper 9 is provided with a bottom cutting lip 10 and side cutting lips 11, and carried by the lips and 75 teeth 12. The bucket 9 is pivotally connected at its upper front corner, as at 13, to the lower end of bracket plates 14 that are secured, as at 15, to the lower end of the dipper handle 3.

A block 16 is secured to and between the bracket plates 14, and it extends forwardly and rearwardly beyond the bracket plates. The block 16 has its rear side inclining upwardly and rearwardly from the lower end of the handle 3, as clearly shown at 16a in Figure 4. A guide sheave 17 and a control sheave 18 are journaled in the block 16. The journal 19 of the sheave 17 is located forwardly and upwardly beyond the pivot 13 of the dipper or bucket 9, and the journal 20 of the sheave 18 is located above the pivot. A loading line 21 extending from a drum, not shown, passes under the sheave 17 and over the sheave 18 and is anchored, as at 22, to the upper rear corner of the dipper or bucket 9.

A block 23 is secured to the top wall of the dipper or bucket 9 and is provided with a 100

downwardly and upwardly inclined top side 23a and an upwardly and rearwardly inclined front side 23b. The top side 23a of the block 23 extends downwardly from the 5 top side of the sheave 18 to the loading line anchor 22, and constitutes a guide and rest for that portion of the loading line that is located between the sheave and anchor. The front side 23b of the block 23 constitutes a 10 stop which contacts with the inclined rear side 16a of the sheave block 16 to limit the upward and rearward swinging movement of the dipper or bucket 9 with respect to the dipper handle 3. When the stop 23b is in 15 contact with the sheave block 16, the dipper or bucket 9 is in loading position with its loading side occupying a plane substantially coincident with the longitudinal axis of the dipper handle 3. The dipper or bucket 9 is 20 adapted to be moved forwardly, to effect the loading thereof, through the medium of the line 21. While it is being wound upon its drum, the loading line 21 exerts an upward and rearward pull upon the dipper or bucket 25 9, with the result that the stop 23b will be firmly held in contact with the sheave block 16 and the dipper or bucket positively held against any swinging movement during the loading thereof.

30 A hoisting line 24 extending from a drum, not shown, passes about the sheave 7 and is secured, as at 25, to the rear end of the sheave block 16. This line provides means through the medium of which the dipper handle 3 35 may be operated to raise the dipper or bucket 9 into its dumping position. The loading position of the dipper or bucket 9 is shown at "A" in Figure 1 and its load dumping position is shown at "B" in Figure 2. After 40 the dipper or bucket 9 is loaded, the loading line 21 is slackened off to permit the dipper or bucket to gravitate to its load sustaining position during the first phase of its movement from loading to dumping position, the 45 load sustaining position of the bucket being shown at "C" in Figure 1.

The manner in which a machine equipped 50 with the dipper or bucket is adapted to be used for the purpose of excavating a ditch is illustrated in Figures 1 and 2. During 55 the loading thereof, the dipper or bucket 9 is moved forwardly and upwardly through the medium of the loading cable 21. After the dipper or bucket has been loaded, the loading line 21 is slackened off and the hoisting line 24 is reeled on its drum to permit the dipper or bucket to gravitate to its load sustaining position and to be raised while occupying this position into a position above 60 the trench. After the dipper or bucket 9 has been raised to this position, the loading line 21 is reeled upon its drum to swing the dipper or bucket into its dumping position. The dipper or bucket 9 will be maintained 65 by gravity in its load sustaining position

while it is being elevated, and when it is in this position, its open side occupies a downwardly and forwardly inclined position with respect to the longitudinal axis of the dipper handle 3.

When the dipper or bucket 9 is in its dumping position, its open side is lowermost and occupies a plane substantially coincident with the longitudinal axis of the dipper handle 3. After the dipper or bucket 9 has been dumped the hoisting line 24 is slackened off and the loading line 21 is reeled on its drum to swing the dipper or bucket downwardly and then forwardly and upwardly to effect the loading thereof. The dumping position 70 of the bucket with respect to the longitudinal axis of the dipper handle 3 is similar to the loading position of the bucket with respect to said axis, and in view thereof, no movement or adjustment of the dipper or bucket with respect to the dipper handle is necessary after the discharging of the load 75 of the dipper or bucket and the loading of the dipper or bucket.

While I have described the principle of the invention, together with the structure which I now consider the preferred embodiment thereof, it is to be understood that the structure shown is merely illustrative and that such changes may be made, when desired, as 80 fall within the scope of the invention as 85 claimed.

I claim:—

In an excavating machine, a boom provided at its upper end with a sheave, a dipper handle, bracket plates secured to and extending solely in a downward direction from the lower end of the dipper handle, a dipper or bucket pivoted at its upper front corner to the lower ends of the bracket plates, a block secured to and between the bracket plates above the pivot of the dipper or bucket, the block extending for a short distance rearwardly beyond the bracket plates and for a considerably greater distance forwardly beyond the bracket plates, the rear end of the block inclining upwardly and rearwardly from the lower ends of the bracket plates and the forwardly extending portion of the block being inclined downwardly, a guide sheave journaled in the lower end of the forwardly projecting portion of the block, a control sheave journaled in the block between the bracket plates, a loading line passing under the guide sheave and over the control sheave and anchored to the upper rear corner of the dipper or bucket, a block secured to the upper side of the dipper or bucket and having an upwardly and rearwardly inclined front side adapted to contact with the inclined rear side of said first block to limit the movement of the dipper or bucket by the loading line, the upper side of said second block inclining downwardly and rearwardly from the upper edge of the control sheave to the upper rear 90 95 100 105 110 115 120 125 130

corner of the dipper or bucket to provide a guide and rest for that portion of the loading line extending from the control sheave to such corner of the dipper or bucket, and a hoisting line passing over the sheave on the boom and secured to the rear end of said first block.

5 In testimony whereof I hereunto affix my signature.

JOE N. SUMMERS.
